RECEIVING APPARATUS FOR TRAIN
CONTROL SYSTEMS

Ralph K. Crooks, Clearfield, Pa., assignor to The
Union Switch and Signal Company, Swissvale,
Pa., a corporation of Pennsylvania

Application February 12, 1943, Serial No. 475,628

4 Claims. (Cl. 246—63)

My invention relates to receiving apparatus for train control systems, and more particularly to such apparatus responsive to alternating current.

Systems using train carried train control apparatus responsive to alternating current are well-known. The alternating current is supplied to a track circuit which includes the track rails and energy is transferred from the track circuit to a train carried receiver mounted on the train in inductive relation to the rails. In some systems the current is non-coded and in other systems it is coded by being periodically interrupted at a given code rate. In systems using non-coded current, the absence of track circuit current results in the most restrictive train controlling indication, and in systems using coded current, either the presence of non-coded current or the absence of current results in the most restrictive indication. The receiver ordinarily includes two inductors mounted on the train with one inductor over each rail, and the two inductors connected in an additive manner. The electromotive force thus induced in the inductors is of the same frequency as the rail current and in coded systems it is also of a code corresponding to the code of the rail current. This received electromotive force is used to govern a master relay which in turn governs the train controlling device, and because the received electromotive force is of a relatively low energy level an amplifier is interposed between the receiver and the master relay. The receiver is connected to the input side of the amplifier through a filter which is tuned to resonance at the frequency of the alternating current to improve the operation and to suppress energy of frequencies other than that used by the train control system.

Shock excitation of the inductors due to propulsion current, extraneous magnetic fields and other conditions may occur. The nature of such shock excitation is such that a very high peak electromotive force may be induced in the inductors. This shock electromotive force may be at a greater or a lesser period than that of the alternating track circuit current, but when its high peak voltage is impressed upon the input circuit including the filter an oscillatory condition is set up and the resulting oscillations may be of sufficient magnitude to cause an operation of the master relay. In systems using non-coded current, a series of such shock excitation waves relatively close together may retain the master relay energized at a time when it should

be released to cause a restrictive indication, and in code systems each such shock excitation may cause an adverse operation of the master relay which in code systems is a code following relay.

Accordingly, a feature of my invention is the provision of train control receiving apparatus incorporating novel means to reduce and minimize the oscillatory condition created by shock excitation.

Again, a feature of my invention is the provision of train control receiving apparatus incorporating novel means to avoid operation of the master relay due to shock excitation of the receiving inductor.

Other objects, features and advantages of my invention will appear as the specification progresses.

The features, objects and advantages embodying my invention I attain by providing a special control device which is incorporated in the receiving apparatus ahead of the filter to reduce and absorb the energy induced in the inductors due to shock excitation to such a low value that the oscillatory condition in the resonant circuits created by such energy is not sufficient to cause an operation of the associated master relay. This control device includes two asymmetric units and means to negatively bias each such asymmetric unit by a voltage slightly greater

than the peak value of the normal control electromotive force picked up by the inductors. This control device is connected to the input circuit ahead of the filter to shunt the relatively high peak value of the electromotive force created by shock excitation before such electromotive force is impressed on the resonant filter, and such shock electromotive force produces very little disturbance in the resonant circuit. The two asymmetric units are poled for one to be effective for excitation of one polarity and the other to be effective for excitation of the other polarity.

I shall describe two forms of apparatus embodying my invention, and shall then point out the novel features thereof in claims.

In the accompanying drawings, Fig. 1 is a diagrammatic view showing one form of apparatus embodying my invention when used with train carried receiving apparatus for a train control system of the code type. Fig. 2 is a diagrammatic view showing another form of apparatus embodying my invention when used with train carried receiving apparatus for a train control system of the code type. Figs. 3 and 4 are diagrams illustrating shock excitations and re-

sultant oscillations of receiving apparatus heretofore provided for train control systems of the class here involved.

Like reference characters are used in the different views to designate similar parts.

Referring to Fig. 1, the apparatus comprises a receiver R, a control device CO, a filter FT, an amplifier AM and a master relay MR, together with the necessary sources of power and circuits.

The receiver R consists of two inductors 3 and 4 mounted on a train in inductive relation to the track rails 1a and 1b, respectively, and which rails are included in a track circuit supplied with alternating current coded at one or more predetermined code rates. The trackway apparatus for supplying such current to rails 1a and 1b is not shown, since it may be of any one of several well-known arrangements and forms no part of my present invention. It is sufficient for a full understanding of my invention to point out that the rails 1a and 1b are arranged in a track circuit which is supplied with alternating current of a preselected frequency and which current may be coded at any one of a plurality of different preselected code rates. In order to better understand my invention, the alternating current supplied to rails 1a and 1b will be considered as having a frequency of 100 cycles per second and as being coded at the code rate of 180 interruptions per minute to reflect clear traffic conditions. It will be understood, however, that my invention is not limited to the above frequency and code rate. It follows that an alternating electromotive force is induced in inductors 3 and 4 when such alternating current flows in the rails and such received electromotive force is of the frequency and code of the rail current. Furthermore, the rail current and in turn the received electromotive force, will have a normal amplitude which falls within limits predetermined for the control system.

Inductors 3 and 4 are connected in series to an input circuit which includes a transformer T1 and filter FT. Specifically the inductors 3 and 4 are connected to primary winding 5 of transformer T1 as will be readily understood by an inspection of Fig. 1, and it follows that an electromotive force corresponding to that picked up by the inductors is created in secondary winding 6 of transformer T1, the electromotive force of secondary winding 6 having a peak value which falls within given limits predetermined for the system.

Filter FT comprises condensers C1 and C2 and a transformer T2, condenser C2 being connected across secondary winding 8 of transformer T2 and condenser C1 being connected in series with primary winding 7 of transformer T2 to a secondary winding 6 of transformer T1, by a circuit connection which forms a part of the input circuit and in which circuit connection the control device CO is interposed.

Control device CO comprises two asymmetric units A1 and A2 and two resistors R1 and R2, units A1 and A2 being connected in series across resistors R1 and R2 in series. The asymmetric units A1 and A2 are disposed with their low resistance, that is, their forward direction, as indicated by arrows placed thereon. These asymmetric units may take different forms and may be, for example, copper oxide rectifier elements assembled in the usual manner except for the fact that the contact plates at each end and at the mid point are extended to form external

circuit terminals and as will appear as the specification progresses, these contact plates are included in associated circuits to provide a check against an open circuit in the connections to the asymmetric units.

The circuit connection between transformer T1 and filter FT can be traced from the left-hand terminal, as viewed in Fig. 1, of secondary winding 6 of transformer T1 through wire 9, mid terminal 10 of resistors R1 and R2 of the device CO, wire 11, condenser C1, primary winding 7 of transformer T2, wire 12, mid contact plate 13 of units A1 and A2 of the device CO, and wire 14 to the right-hand terminal of secondary winding 6. It is to be noted that control device CO provides two paths across this portion of the input circuit, one path extending from mid terminal 10 connected to wires 9 and 11 of one side of the input circuit, through resistor R2 and asymmetric unit A2 in its forward direction to mid contact plate 13 connected to wires 12 and 14 of the other side of the input circuit. The second path extends from mid contact plate 13 through asymmetric unit A1 in its forward direction and resistor R1 to mid terminal 10. The function of the control device CO will be made clear presently. The input circuit is connected to the amplifier AM which in Fig. 1 comprises two stages including electron tubes 15 and 16, respectively. Each tube 15 and 16 is provided with a plate, a control grid and a cathode or filament and is arranged for operation by current supplied from the usual train carried 32 volt source of direct current whose terminals are shown at B32 and C. The 32 volts are converted to 300 volts for use with the plate circuits of the tubes of the amplifier by a motor generator MG whose motor 17 is connected to terminals B32 and C and whose generator 18 is provided with terminals B300 and N300 from which direct current of 300 volts is obtained, the negative terminal N300 of generator 18 being connected to terminal C of the current source because this terminal serves as a common terminal.

Control grid 23 and filament 20 of tube 15 are connected to the output side of filter FT by a circuit that can be traced from control grid 23 through secondary winding 8 and condenser C2 in multiple, wire 28, contact plate 22, asymmetric units A1 and A2 in their forward directions to contact plate 21 and thence to filament 20. Hence receiver R is coupled to the control grid of tube 15 through the input circuit including transformer T1 and filter FT. Filter FT is proportioned to tune the input circuit to resonance at the frequency of the alternating track circuit current, that is, in the case here assumed, to resonance at 100 cycles per second.

The filaments of tubes 15 and 16 are connected in series with control device CO to the 32 volt source of current, the circuit extending from terminal B32 through resistor 34, filaments 19 and 20 of tubes 16 and 15, respectively, control device CO and to terminal C. The asymmetric units A1 and A2 are poled to block the flow of filament current and thus the filament current flows through contact plate 21, resistors R1 and R2 in series and contact plate 22, and creates a voltage drop across each resistor. Preferably, the two resistors R1 and R2 are alike and the voltages across the two are substantially equal. It is to be observed that the top terminal of resistor R1 is positive with respect to the mid ter-

rninal 10 and the mid terminal 10 is positive with respect to the lower terminal of resistor R2.

These voltages across resistors R1 and R2 serve as bias voltages for asymmetric units A1 and A2. That is, the asymmetric unit A1 as disposed in its circuit path across the input circuit as explained hereinbefore, is biased by the voltage drop in resistor R1, and asymmetric unit A2 as disposed in its circuit path across the input circuit is biased by the voltage drop of resistor R2. For example, the half cycle of the alternating electromotive force created in secondary winding 6, that causes the left-hand terminal of the winding to be positive, is opposed in flowing through the path extending from mid terminal 10 through resistor R2 and unit A2 in its forward direction to contact plate 13 and wire 14 to the left-hand terminal of winding 6 by the direct voltage drop created in resistor R2 by the filament current. Similarly, the half cycle of the alternating electromotive force that causes the right-hand terminal of winding 6 to be positive, is opposed in flowing through the path extending from contact plate 13 through unit A1 in its forward direction and resistor R1 to mid terminal 10 by the direct voltage drop of resistor R1 created by the filament current. That is to say, asymmetric units A1 and A2 are provided with what I shall call a negative bias voltage due to the voltage drop of the resistors R1 and R2, respectively.

It is to be seen, therefore, that receiver R is connected to the control grid of the first stage tube of the amplifier AM by an input circuit which includes filter FT, and the control device CO is connected to the input circuit in such a manner as to form two biased shunt paths across the circuit ahead of the filter. Furthermore, in the grid circuit for tube 15, the direct voltage drop across resistors R1 and R2 of control device CO serves as a grid bias voltage for that tube.

Plate 24 of tube 15 is connected to terminal B300 through primary winding 25 of a coupling transformer T3, and since filament 20 of tube 15 is connected to terminal C the tube is provided with a plate circuit in which there appears in amplified form the coded alternating electromotive force applied to the grid of tube 15 through the input circuit. The transformer T3 serves to couple the plate circuit of tube 15 to the grid circuit of the second stage tube 16, grid 26 and filament 19 of tube 16 being connected across secondary winding 27 of transformer T3. The plate 29 of tube 16 is connected to terminal B300 through primary winding 30 of an output transformer T4, a by-pass condenser 31 being connected across winding 30. Secondary winding 32 of transformer T4 is connected to code following master relay MR. Relay MR is preferably of the stick polar type. Consequently at the beginning of each on code period of rail current and in turn at the beginning of each on period of the electromotive force picked up by inductors 3 and 4 and applied to the amplifier through the input circuit, the direct current component of the plate circuit current of tube 16 is varied in one sense due to the amplifying action of tubes 15 and 16 and an electromotive force of a given polarity is induced in secondary winding 32 of transformer T4 to operate relay MR to a corresponding position. Then at the end of each on code period of the rail current, and in turn at the end of each on period of the electromotive force induced in inductors 3 and 4, the direct current component of the plate circuit current

of tube 16 is varied in the opposite sense and an electromotive force of a polarity opposite to that of said given polarity is induced in secondary winding 32 to operate master relay MR to its other position. Relay MR controls through its contact member 33 train controlling devices, such train controlling devices being governed according to the code rate at which member 33 is operated but these devices are omitted from the drawings for the sake of simplicity since they would be of standard arrangement and form no part of my present invention.

The control device CO is proportioned for the bias voltage provided for units A1 and A2 due to the voltage drop at resistors R1 and R2 as explained hereinbefore, to be of a value slightly greater than the peak value of the normal alternating electromotive force appearing across secondary winding 6 of transformer T1 due to the electromotive force picked up by inductors 3 and 4 in response to the normal value of the track circuit current. Consequently, under normal condition, with no shock excitation present, the alternating electromotive force is passed by filter FT and applied to the amplifier with little attenuation, the control device CO not affecting the electromotive force because the negative bias voltage created by resistors R1 and R2 serves to prevent the flow of current through the units A1 and A2 in their forward directions.

Referring now to Fig. 3, the top graphs represent two time spaced electromotive forces created in the train carried inductors due to shock excitation. That is, a shock excitation may create a half-wave electromotive force of either positive or negative polarity. Such a shock electromotive force when applied to the resonant input circuit of receiving apparatus as heretofore provided creates a group of oscillations as illustrated in the lower graphs of Fig. 3. Such a group of oscillations when amplified may result in an effective energization of the master relay. Assuming the inductors 3 and 4 of Fig. 1 are shock excited and an electromotive force of relatively high peak voltage is created therein, the control device CO functions to shunt and reduce the higher values of this shock voltage. For example, if the wave is one that causes the left-hand terminal of secondary winding 6 to be positive, the higher values of the wave are shunted due to current flowing through resistor R2 in opposition to the normal voltage drop of resistor R2, asymmetric unit A2 in its forward direction and back to the other terminal of winding 6. Similarly, if the wave is one that causes the right-hand terminal of winding 6 to be positive, the higher values of the wave are shunted due to current flowing through resistor R1 in opposition to its normal voltage drop and asymmetric unit A1 in its forward direction and back to the left-hand terminal of winding 6. That is to say, all values of the shock wave above the predetermined normal peak value of the 100 cycle electromotive force are shunted through the asymmetric unit of the control device. With the shock wave thus reduced to leave only the lower values of the wave to be applied to the filter, the oscillations set up are too small to cause an effective energization of the master relay. This suppressing action of the control device is brought about by the fact that the impedance of the asymmetric units, when they are conductive, is very much less than the impedance of the circuit from the secondary winding 6 to the filter and most of the voltage of the wave is consumed

by winding 6 due to the current flowing through the asymmetric unit. In some cases, the shock excitation may cause a full cycle wave, as illustrated in the upper graph of Fig. 4. Such wave would in apparatus heretofore provided create oscillations similar to that illustrated by the lower graph of Fig. 4. In this case the control device CO of Fig. 1 serves to reduce the higher values of each half cycle of the wave because one asymmetric unit is poled to pass one half cycle and the other asymmetric unit is poled to pass the other half cycle.

It is to be observed that in the event the alternating rail current becomes of an abnormal high amplitude and the electromotive force picked up by the inductors is correspondingly high, and above the normal predetermined value, the higher values of this abnormal electromotive force will be shunted by the control device CO but with no detrimental effect on the normal operation of the apparatus because energy of normal value will be passed to the amplifier.

Referring to Fig. 2, the apparatus is the same as in Fig. 1, except the control device CO is replaced by a control device CO1, and which latter device includes a duodiode tube DT and a resistor R3. Tube DT is provided with a heater or filament 35, two anodes 36 and 37 and two cathodes 38 and 39; anode 36 and cathode 38 forming one diode and anode 37 and cathode 39 forming a second diode. Filament 35 and resistor R3 in series are interposed in the filament circuit of tubes 15 and 16 in a manner similar to resistors R2 and R1 of Fig. 1. The voltage drop through resistor R3 due to the filament current serves to provide a bias voltage for the diode 37-39 and the voltage drop through filament 35 serves to provide a bias voltage for diode 36-38. In Fig. 2, secondary winding 6 of transformer T1 is connected to primary winding 7 of transformer T2 of the filter through wire 40, mid terminal 41 between resistor R3 and filament 35, wire 42, condenser C1, primary winding 7 and wire 43 to the other terminal of winding 6. Control device CO1 provides two shunt paths across this portion of the input circuit. One path extends from mid terminal 41 through filament 35, wire 44 and diode 36-38 in its low resistance direction to wire 43. The second path extends from wire 43 through diode 37-39 in its low resistance direction, wire 45 and resistor R3 to mid terminal 41. The direct voltage drop of filament 35 opposes the flow of current through the first path in response to the alternating electromotive force of secondary winding 6, and the direct voltage drop of resistor R3 opposes the flow of current through the second path in response to the alternating electromotive force of secondary winding 6. That is, diode 36-38 is provided with a negative bias voltage equal to the voltage drop of filament 35 and diode 37-39 is provided with a negative bias voltage equal to the voltage drop of resistor R3. The remaining portion of the apparatus of Fig. 2 is the same as that of Fig. 1 and the description of the apparatus need not be repeated.

Filament 35 and resistor R3 are proportioned for each to provide a voltage drop slightly greater than the peak value of the normal alternating electromotive force created in secondary winding 6 due to the alternating rail current. Hence when an alternating electromotive force is picked up by inductors 3 and 4 of Fig. 2 due to the usual track circuit current, the corresponding electromotive force created in secondary winding 6 is

transferred and applied through filter FT to the amplifier, the control device CO1 not affecting the electromotive force because of the bias placed on the diodes. If inductors 3 and 4 of Fig. 2 are shock excited and the wave is one that causes the left-hand terminal of secondary winding 6 to be positive, the higher values of the wave cause current to flow through the path including filament 35 and diode 36-38 in its forward direction, and if the wave is one that causes the right-hand terminal of winding 6 to be positive, the higher values of the wave cause current to flow through diode 37-39 in its forward direction, and resistor R3, and this shunting action caused by the control device CO1 serves to reduce the shock wave to such a low value that the oscillations produced in the filter are not of sufficient magnitude to cause an effective operation of the master relay. That is to say, the control device CO1 functions to reduce and suppress shock excitation in substantially the same manner as explained for control device CO of Fig. 1.

It should be pointed out that the control devices CO and CO1 can be used with a single stage amplifier or an amplifier with more than two stages if desired. Also, they can be used with a low voltage amplifier, that is, an amplifier arranged to operate on the 32 volts of the usual train carried source without voltage conversion. Again, it is to be observed that the transformer T1 may be omitted and the inductors connected directly to the input side of the filter, the use of transformer T1 serving to insulate the terminal C of the train carried source of current from the inductors to avoid possible ground conditions of the circuit.

Apparatus embodying my invention has the advantage that train carried train controlling devices are substantially free from being falsely operated due to shock excitation caused by magnetized wheels, magnetized rail spots, propulsion current, loose receiver and similar conditions.

Although I have herein shown and described only two forms of receiving apparatus for train control systems embodying my invention, it is understood that various changes and modifications may be made therein within the scope of the appended claims without departing from the spirit and scope of my invention.

Having thus described my invention, what I claim is:

1. In train control apparatus including an electron tube amplifier and a receiver mounted on a train in inductive relation to the track rails to receive an electromotive force in response to an alternating track circuit current, the combination comprising, a filter including a transformer having independent primary and secondary windings and a condenser and said filter tuned to resonance at the frequency of said alternating track circuit current, a control device including two asymmetric units in series connected across two resistors in series, said asymmetric units poled with their forward directions in the same direction, a filament circuit for said amplifier tube and including a source of direct current and said control device, said control device disposed for its asymmetric units to block the filament current and cause such current to flow through said resistors to create a voltage drop across said resistors, an input circuit to connect said receiver to said primary winding of said filter transformer, said control device having a mid terminal of its resistors connected to one side

of said input circuit and a mid contact plate of its asymmetric units connected to the other side of the input circuit to reduce excitation waves created in said receiver in excess to the voltage drop across each resistor as created by the filament current, and other circuit means including said control device to connect said secondary windings of said filter transformer to a control grid and cathode of said tube to apply to said tube said electromotive force as passed by said filter with the tube provided with a grid bias voltage due to said voltage drop of said resistors.

2. In train control apparatus including an electron tube amplifier and a receiver mounted on a train in inductive relation to the track rails to receive an electromotive force in response to an alternating track circuit current, the combination comprising, a filter including a transformer having independent primary and secondary windings and a condenser and said filter

tuned to resonance at the frequency of said alternating track circuit current, a control device including two asymmetric units connected in series across two resistors in series; a filament circuit for said amplifier tube and including in series a source of direct current, said filament, a first outside contact plate of said asymmetric units, said resistors in series in multiple with said asymmetric units in series and a second outside contact plate of the asymmetric units; said units poled to block the flow of the filament current to create a voltage drop across said resistors due to the filament current flowing through the resistors, an input circuit including a mid contact plate of said asymmetric units and a mid terminal of said resistors to connect said receiver to said primary winding of said filter transformer to pass said electromotive force to the filter and to reduce shock waves created in said receiver greater than the voltage drop of each resistor, and a grid circuit including said resistors in series and said first outside contact plate to connect said secondary winding of the filter transformer to a control grid and filament of said tube to apply said electromotive force to the tube with a tube grid bias voltage equal to the voltage drop of said resistors.

3. In train control apparatus including an electron tube amplifier and a receiver mounted on a train in inductive relation to the track rails to receive an electromotive force in response to an alternating track circuit current, the combination comprising, a filter including capacitance and a transformer having independent primary and secondary windings and said filter tuned to resonance at the frequency of said alternating current, a control device including a resistor and

a duodiode tube having a filament; a filament circuit including in series a source of direct current, the filament of said amplifier tube, said resistor and the filament of said duodiode tube; 5 an input circuit to connect said receiver to said primary winding of the filter transformer and said secondary winding of the filter transformer to a control grid and cathode of said amplifier tube, said control device having a mid terminal of said resistor and the filament of the duodiode tube connected to one side of said input circuit ahead of the filter and a common terminal of the anode of one diode and the cathode of the other diode connected to the other side of the input circuit ahead of the filter, and said control device having a connection from the cathode of said one diode to the filament of the amplifier tube and another connection from the anode of said other diode to the filament of the duodiode tube.

4. In train control apparatus including an electron tube amplifier and a pair of inductors mounted on a train in inductive relation to the track rails to receive an electromotive force in response to an alternating track circuit current, the combination comprising, a first transformer having a primary winding connected to said inductors, a filter including a transformer and capacitance and tuned to resonance at the frequency of said alternating current, a control device having two multiple paths one of which paths includes two asymmetric units in series and the other of which paths includes two resistors in series; a filament circuit including in series a source of direct current, a filament of said amplifier tube and said control device; said asymmetric units poled to block the flow of such filament circuit current to cause the current to flow through said resistors to create a voltage drop across each resistor, a first circuit to connect a secondary winding of said first transformer to a primary winding of said filter transformer, a second circuit to connect a secondary winding of said filter transformer across a control grid and said filament

45 of said amplifier tube, and said control device interposed in said second circuit between said secondary winding of the filter transformer and said tube filament and having a mid terminal of its resistors connected to one side of said first circuit and a mid terminal of its asymmetric units connected to the other side of said first circuit whereby said control device provides a normal grid bias voltage for said tube, reduces shock waves created in said inductors and insulates said 50 inductor from said filament circuit current source.

RALPH K. CROOKS.
